POWER CHAIN SAW ENGINE ASSEMBLY

Ulrich O. Densow and David L. Dickson, Peterborough,
Ontario, Canada, assignors to Outboard Marine Corporation,
Waukegan, Ill.

Filed Feb. 12, 1971, Ser. No. 115,149

Term of patent 14 years

Int. Cl. D8—03

U.S. Cl. D8—65

FIG. 1 is a perspective view showing the rear and one side of the power chain saw engine assembly with a cutter bar, roller nose, and chain fragmentarily shown in broken lines for illustrative purposes only.

FIG. 2 is a side view of the opposite side of the power chain saw engine assembly shown in FIG. 1.

FIG. 3 is a view of the bottom of the power chain saw engine assembly shown in FIG. 1.

FIG. 4 is a view of the front of the power chain saw engine assembly shown in FIG. 1.

We claim:

The ornamental design of a power chain saw engine assembly, as shown and described.
